UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,244,573.

Specification of Letters Patent. Patented Oct. 30, 1917.

Application filed June 3, 1911. Serial No. 631,115.

To all whom it may concern:

Be it known that I, WALTER WRIGHT, a citizen of the United States, residing in New York, in the county of New York and State of New York, have invented certain new and useful Improvements in Combined Type-Writing and Computing Machines, of which the following is a specification.

This invention relates to the mechanism which produces the step-by-step denominational movement between the master wheels and the systems of computing wheels of a combined typewriting and computing machine employing a plurality of simultaneously operating computing heads.

In my application No. 574,813, filed August 1, 1910, are shown means for automatically connecting and disconnecting a traveling member of a computing mechanism with the main carriage of the typewriter, for cross-adding and other purposes. The traveling member of the computing mechanism was connected by means of a lever to a latch or hook, which connected the typewriter carriage to said traveling member; the connection and disconnection of said hook and typewriter carriage being automatically effected. The usual column-stop rack of a tabulator was employed for engagement by said hook, so that the operator when setting the column-stop or device to position for writing figures in the proper column on the page could, by the same act, provide for automatically connecting the computing mechanism with the carriage to add the numbers written in such column.

In my application 569,502, two or more computing devices are simultaneously connected with and disconnected from the typewriter carriage. In my application 574,813, a single master wheel is connected to the carriage by means of a lever and hook. According to the present invention, the lever is forked to engage two master wheels placed one over the other, although it will be understood that said forked lever may be caused to reciprocate a plurality of systems of computing wheels in place of a plurality of master wheels, as illustrated in the drawings.

Other features and advantages will hereinafter appear.

In the accompanying drawings,
55 Figure 1 is a sectional elevation from front

to rear, showing the present improvements applied to an Underwood front strike combined typewriting and computing machine.

Fig. 1^a is an elevation taken on the opposite side from Fig. 1, of the forward end 60 of the lever, showing its connection to two master wheel carriages.

Fig. 2 is a rear elevation of the machine.

Fig. 3 illustrates the manner of automatically disconnecting the traveling members 65 of the computing mechanisms from the typewriter carriage.

Fig. 4 is a sectional plan of that portion of the upper computing mechanism involved in the present invention.

Fig. 5 is a perspective view of one of the hooks and its appurtenances.

Fig. 6 is a sectional view showing the hook in cross-section, and also the spring by which it is lifted to connect it with the 75 typewriter carriage.

In the Underwood machine, numeral keys 1 depress levers 2 to vibrate bell cranks 3, and swing type bars 4 up to strike rearwardly against the front side of a platen 80 5. Said platen is mounted on a carriage 6, running on tracks 7, 8, and is driven by a spring barrel 9, and also has a rack 10 meshing with a pinion 11 connected to an escapement wheel 12, the escapement dogs, 85 which are operated at every key stroke, being omitted. The rack 10 is hung on arms 13, so that it may be lifted from the pinion 11 to release the carriage.

Tabulator keys 14 are mounted upon levers 15, which, at their rear ends, raise the stop rods 16, having decimal stops 17 at their upper ends. These stops may coöperate with interchangeably adjustable column stops 18 of the ordinary type; said column stops being inserted, as required, in notches 19, 20, formed in the top and bottom of a bar 21, which is fixed to the carriage 6.

Each decimal stop-rod has a shoulder 22 100 coöperating with a universal bar 23, which rocks about a pivot 24, and has an arm 25, which draws on a link 26 and vibrates a lever 27, the latter fulcrumed at 27^a and carrying a roll 27^b to run upon the under side of the rack bar 10, and lift the latter from the escapement pinion 11, whenever a key 14 is depressed. As so far described in detail, the parts are in common use on said Underwood typewriting machine.

The lower computing mechanism includes a drive shaft 28, having a bevel pinion 29 meshing with a pinion 30 upon a square shaft 31, the latter being splined to a master-wheel 32, which moves along the shaft and has spurs or teeth 33 to engage an internal set of teeth 34 formed upon a gang of computing wheels 35, the latter mounted in a casing 36 and also having exterior teeth 37 to mesh with gears 38, the latter having number wheels 39. The master wheel 32 is swiveled in a traveling hollow mandrel or arbor 40, within which the master wheel shaft 31 may project, the swivel-joint being shown at 41, and permitting the master-wheel 32 to be rotated by the shaft 31, while said master wheel is caused to travel in axial direction by the mandrel or arbor 40.

The mechanism so far described in detail forms no part of the present invention, and the drive shaft 28 may be driven and controlled either directly by the numeral keys 1 or in any other suitable manner, as for instance in the manner set forth in my pending application No. 569,502, filed June 29, 1910, which application embodies claims covering features herein disclosed; the present application being intended only to disclose and cover the forked form of the connecting guide-lever 42. Since the driving means for said shaft form no part of the present invention, it is deemed unnecessary to illustrate the same. The shaft, it will be understood, is rotated automatically upon the depression of any of the numeral keys 1, the extent of rotation depending upon which key is depressed.

The mandrel 40 is moved endwise by means of a forwardly and rearwardly extending lever 42, pivoted midway of its ends by means of gudgeons 43, so as to swing in a horizontal plane. At its forward end the lever is slotted at 44 to engage a pin 45 projecting from the carriage which carries the mandrel 40; said carriage comprising a tube 46 sliding upon a fixed rod 47, and also an arm 48, sliding upon a fixed horizontal rod 49; the mandrel 40 being secured to the forward end of the arm 48 by means of a set-screw 50. The movement of the mandrel 40 is of course only sufficient to enable the master wheel 32 to travel the length of the gang of computing wheels 35, one of which is provided for each number wheel 39. The rod 47 cooperates with two similar rods or studs 47^a and 47^b, all projecting from a framework plate or bracket 47, to carry a small plate 47^d, which also supports the end of rod 49. It will be seen that 47^a and 47^b, Fig. 1, carry the casing 36.

At its rear end, the lever 42 has a slot 51 to engage a pin 52 projecting down from a slide 53, the latter carrying the stem 54 of a hook 55, adapted to engage lugs 56 formed

upon said stops 18 or upon blades or tappets 57 which are forked to fit into the double rack 19, 20, for connecting the paper carriage 6 to the master wheel 32 to cause the latter to travel step-by-step with the paper carriage.

The slide 53 works in a tubular guide or housing 58, which is slotted on its under side at 59 to permit the pin 52 to pass down to the lever 42. The stem 54 of the hook 55 passes through a longitudinal perforation in the slide 53, and is adjustably secured to the latter by set screws 60, Fig. 2. The rack 21 has at 60^a the usual provision for longitudinal adjustment. The slide 53 has 80 a feather 61, to fit into the slot 59, to prevent the slide and the hook from turning in the tube.

The hook has a notch 62 to enable it to engage any of the lugs 56. The hook normally springs up to engage the adjacent lug. For this purpose the hook may be made resilient or flexible, and a compression spring 63 Fig. 6 may be employed to aid or cause the upward movement of the hook; said spring housed in a boss 64, and confined by a screw 65, and pressing a plunger 66 up against a straight portion of the under side of the hook, thus holding the latter up while permitting it to move freely endwise. The boss 64 is formed on a bushing 67, which is vertically slotted at 68 to form a guide for the hook; said bushing serving as a plug to close this end of the tubular housing 58.

As so far described in detail, the mechanism is disclosed and claimed in my said pending application 574,813. According to the improvement made the subject of the present application, the lever 42 is forked at 68^a, the upper fork being connected to a carriage 68^b which is similar in all respects to said carriage 48, forming part of an upper computing mechanism, the parts of which are designated by the same letters as the lower computing mechanism already described, with the addition of the exponent x. As will be seen at Figs. 1 and 1^a, the computing mechanisms are placed one directly over the other; and both master wheels are driven by the single drive shaft 28, which is extended at 68^c to carry the pinion 29^x, to rotate the upper master wheel shaft in the manner already described in relation to the lower master wheel shaft, so that computation may be performed simultaneously on the upper and lower computing heads. The lever 42 and its forks being rigid, and the lever being firmly pivoted upon a wide bearing, it will be seen that the lever serves as a guide or controller, whereby the upper and lower master wheels are caused to move accurately in unison.

The present invention relates solely to the forking of the lever, and the following details of description also are disclosed and 130

covered by claims in my said application 574,813.

When the hook is in engagement with one of said lugs 56, it is carried with the paper carriage 6 in the direction of the arrow at Fig. 2, that is, to the right to cause the lever 42 to swing upon its pivot and thereby drive the mandrels 40 and 40^x, and the master wheels 32 and 32^x to the left at Fig. 4. As the keys 1 are operated to write figures in the column, the master wheels 32 and 32^x are correspondingly rotated in any usual or suitable manner, to rotate the corresponding computing wheels 35 and 35^x. When the master wheels have advanced past the computing wheels 35 and 35^x of lowest denomination, a cam 69 formed on the hook 55 engages a projection 70 fixed upon the framework of the machine, and is thereby forced downwardly, to withdraw the hook 55 from that lug 56 with which it has been in engagement. As soon as the hook is released, a returning spring 71 connected to the lever 42 swings the latter in the opposite direction, carrying the master wheels 32 and 32^x backwardly or to the right at Fig. 4, that is, toward the computing wheels 35 and 35^x of highest denomination; this movement continuing until the hook 55 engages the succeeding lug 56, said hook being pressed up to engage said lug by means of the spring 63, and the hook becoming fully seated in the notch 62, as at Fig. 5. The writing of the numbers in the succeeding column will now proceed, and said numbers will be accumulated on each of said systems of computing wheels by the number wheels 39 and 39^x, in the manner already referred to.

When returning the carriage 6 to begin a

new line of writing, if the hook 55 is in engagement with one of the lugs 56, it is carried to the left at Fig. 2, until a cam edge 72 thereon strikes a stud or roller 73, which may be pivoted upon a screw 74, threaded into the top of the boss 64; and by means of said roller or obstruction, the hook is cammed downwardly and released from the lug 56. The spring 63 immediately lifts the hook again, and the lugs 56 in succession ride freely over a bevel or point 75 formed on the tip of the hook; the last lug in the series being caught and held by the hook when the carriage begins to run in letter-feeding direction.

Variations may be resorted to within the scope of the invention.

Having thus described my invention, I claim:

In a combined typewriting and computing machine, the combination with two master members, mounted one above another, computing members controlled by said master members, and a typewriter carriage, of means for moving said master members accurately in unison, comprising a rigid guide-lever pivoted intermediate its ends and connected at one end to said carriage, said master members being connected to the other end of said lever; said other end having rigid forks, one fork extending above the other, the upper master member being connected to the upper fork and the lower master member to the lower fork.

WALTER WRIGHT.
